HYDROCARBON OIL CONVERSION

Victor Stapleton, Jackson Heights, N. Y., assignor
to The Texas Company, New York, N. Y., a corporation of Delaware

Application July 31, 1934, Serial No. 737,702

3 Claims. (Cl. 196—58)

My invention relates in general to the conversion of hydrocarbon oil to obtain a motor fuel in the gasoline boiling range, coke and fuel oil as final products.

In the usual combined coking and cracking operations heretofore practiced it has been customary to return the residuum, in the nature of cracked tar and other heavy tar-like products, resulting from the cracking of a relatively clean oil, together with unvaporized constituents of fresh oil directly to a coking chamber receiving a stream of oil at cracking temperature wherein they are retained and reduced to coke. It has been found that such cracked tars are not the most desirable coking stock and when mixed with unvaporized fresh charge, as well as with heavy condensate from the cracked vapors, they tend to cut down the capacity of the entire system as well as produce a coke having certain disadvantages. This decrease in the capacity of the system is due to the highly refractory nature of the cracked tar, hence a poor cracking stock, which results in the building up of a large quantity of heavy liquid in the coking chamber with the consequent frothing or foaming thereof. Moreover, coke obtained in an operation of this character when using cracked tar as part of the coking stock has been found to be inferior to coke obtained from a less cyclic material.

In accordance with my invention, there is provided a combined coking and cracking operation in which cracked tars and other heavy tar-like products are not returned to the coking operation, thereby increasing the capacity of the operation and producing a superior coke. While the cracked tars deter from the overall efficiency of the entire operation as well as from the quality of the coke produced, these materials if properly handled are quite satisfactory and possess qualities that enable a refiner to dispose of them as a readily marketable commercial fuel oil. When practicing my invention these tar-like products are withdrawn from the cracking system as fuel oil or they may be passed to a zone maintained at a lower pressure than that maintained in the cracking system to thereby remove lighter vaporizable constituents therefrom. By flashing these products it is possible to obtain additional oil suitable as cracking stock in addition to an overhead naphtha fraction and a commercial fuel oil.

My invention contemplates introducing a charge oil into a dephlegmating tower receiving cracked vapors. The cracked vapors prior to being contacted with the charge oil are dephleg-

mated to separate therefrom the cracked tar and other heavy tar-like products these separated products being separately withdrawn from the dephlegmating tower. The charge oil introduced into the dephlegmating tower may be obtained from a fresh source extraneous to the system or if desired the charge may comprise condensate oil, resulting from flashing the cracked tars, and unvaporized constituents of fresh oil introduced into the flashing zone to contact the vaporous constituents therein.

The charge oil thus introduced into the dephlegmating tower receives heat from the upwardly rising cracked vapors therein thereby separating vaporizable constituents therefrom. The unvaporized constituents of the charge oil, together with any heavy condensate condensed from the cracked vapors, are collected in the dephlegmating tower as a coking stock separately from the cracked tars. The thus collected coking stock is conducted to a coking chamber receiving cracked products and therein retained to be reduced to coke.

From the foregoing it will be apparent that the cracked tars or heavy tar-like products, are not returned to the coking chamber with the more desirable coking stock thereby improving the operation and producing a superior coke. This stock, is however, separately withdrawn from the cracking operation and recovered as a valuable commercial fuel oil.

In order to make my invention more clearly understood, I have shown in the accompanying drawing, means for carrying the same into practical effect without limiting the improvements in their useful application to the particular constructions which, for the purpose of explanation, have been made the subject of illustration.

The single figure illustrates diagrammatically one form of apparatus for carrying out my invention.

Referring to the drawing there is shown a furnace 1 having a preheating coil 2 and a cracking coil 3 preferably heated preponderantly by radiant heat disposed therein. The cracking system may comprise in addition to the furnace 1, a coking chamber 4, a dephlegmating tower 5 divided into an upper portion 6 and a lower portion 7 by means of a trap-out tray 8, a fractionating tower 9, such as a conventional bubble tower, a condenser 11 and a distillate receiver 12 having a valved gas outlet 13 and a valved distillate withdrawal line 14.

A clean condensate oil resulting from fractionation of vapors in the fractionating tower 9, 55

- as will be hereinafter explained, may be withdrawn from the lower portion of the fractionator 9 through a line 15 and forced under super-atmospheric pressure, by means of a pump 16, through the coils 2 and 3 wherein it is raised to the desired cracking temperature. The cracked products may be conducted from the cracking coil 3 through a transfer line 17 controlled by a suitable pressure reduction valve 18, two of which are shown but only one of which is actually used for any one particular operation, as will be hereinafter explained, into the coking chamber 4. The condensate oil passing through the heating coils 2 and 3 is preferably heated under vapor phase cracking conditions and the vapors upon entering the coking chamber 4 pass upwardly therein undergoing additional cracking and may be conducted through a line 19, controlled by a pressure reduction valve 21, into the lower portion 7 of the dephlegmating tower 5.
- The vapors introduced into the lower portion 7 of the dephlegmator are therein dephlegmated to separate heavy cracked residuum contained therein, such as cracked tar and heavy tar-like products, and the thus dephlegmated vapors are passed through a passage in the trap-out tray 8 to the upper portion 6 of the dephlegmating tower. The vapors passing through the upper portion 6 of the dephlegmator are further dephlegmated therein. A fresh charge oil of a character hereinbefore described is introduced into the upper portion 6 to contact the upwardly rising vapors to separate relatively heavy constituents as a condensate from the vapors and effect vaporization of any light vaporizable constituents of the fresh oil. These condensed constituents of the vapors and unvaporized portions of the charge oil are collected on the trap-out tray 8. The thus dephlegmated vapors may be conducted from the dephlegmator 5 through a line 22 into the lower portion of the fractionating tower 9 and therein subjected to fractionation to separate out a clean reflux condensate for return to the heating coils through the line 15. The fractionated vapors leaving the fractionating tower 9 may be conducted through the line 23 into the condenser 11, wherein they are condensed, and then passed through a line 24 to the distillate receiver 12.
- In accordance with my invention, the heavy tar-like products collected in the lower portion 7 of the dephlegmator 5 may be withdrawn from the cracking system through a line 25. This cracked tar may be passed to suitable storage by opening a valve 26 in the line 25 or if desired may be conducted to a flash chamber maintained under reduced pressure. As shown, the cracked tar may be conducted through a line 28, a valve 27 therein being opened and the valve 26 being closed, to a flash chamber 29 having an upper portion 31 and a lower portion 32 separated from each other by means of a trap-out tray 33. The pressure maintained on the cracked tar passing to the flash chamber 29 is reduced by the valve 27. The cracked tar upon entering the flash chamber is partially vaporized and the unvaporized constituents comprising the desired fuel oil are collected in the lower portion 32 and withdrawn therefrom through a line 32'.
- The vaporous constituents resulting from the flashing of the cracked tar pass upwardly in the flash chamber 29 through a passage in the trap-out tray 33 into the upper portion 31 wherein they are dephlegmated. A fresh charge oil, in the nature of a heavy oil, such as a reduced crude

or a crude, preheated if desired, may be introduced into the upper portion 31 of the flash chamber 29 through a pipe 34 by means of a pump 35. The fresh charge upon contacting the upwardly rising vapors is thus heated and the lighter or lower boiling vaporizable constituents separated therefrom. The unvaporized portion of the fresh charge oil, together with condensate resulting from the dephlegmation of the upwardly rising vapors, are collected on the trap-out tray 33 to constitute the charge oil for the dephlegmating tower 5.

The vaporous constituents leaving the flash chamber 29 of a low boiling character in the nature of naphtha may be conducted through a line 36 to a condenser 37 wherein they are condensed and passed through a line 38 to a distillate receiver 39 having a valved gas outlet 41 and valved distillate withdrawal line 42. Under certain conditions of operation the stock collected in receiver 39 may comprise kerosene and/or light gas oil, in addition to naphtha.

The unvaporized constituents of the fresh charge introduced into the flash tower 29 and the condensate resulting from dephlegmation of the flashed vapors from the cracked tar which are collected on the trap-out tray 33 may be withdrawn through a line 43 and forced by means of a pump 44 through a line 45 into the upper portion of the dephlegmating tower 5. The dephlegmating tower 5 is as shown provided with suitable plates both above and below the trap-out tray 8 for facilitating the desired dephlegmation. The charge oil thus introduced into the upper portion of the dephlegmator 5 flows downwardly over the plates in the upper portion 6 and contacts the upwardly rising cracked vapors. Vaporizable constituents of the charge oil suitable as charging stock for the cracking coil 3 are thus driven off and the unvaporized constituents together with heavy condensate resulting from the dephlegmation of the cracked vapors in the upper portion 6 are collected on the trap-out tray 8 to constitute a coking stock.

As contemplated by my invention, and in carrying out the aforementioned objects, a fresh charge oil from an extraneous source may be introduced directly into the upper part of the dephlegmator 5, this oil being preheated, for example by passing it through a preheating coil 50 positioned in the lower portion 7 of the dephlegmator 5. When operating in this manner, the valve 27 is closed and the valve 26 opened, thus providing for withdrawal of the cracked residuum from the lower portion 7 through the line 25.

The coking stock collected on the trap-out plate 8 which comprises unvaporized constituents of the fresh charge and condensate resulting from dephlegmation of the cracked vapors but free from cracked tar-like products may be withdrawn through a line 46 and forced by means of a pump 47 to the stream of clean condensate undergoing cracking. As shown, the coking stock may be introduced either on the high or low pressure side of the pressure reduction valve 18 thereby causing the stock so introduced to be raised to a cracking temperature and accomplishing some viscosity-breaking of this stock prior to its entry into the coking chamber 4. If desired the coking stock may be passed to an intermediate point 70 of the cracking coil 3 in order to impart more heat thereto before being passed to the coking chamber 4 to cause even more cracking thereof of a viscosity breaking nature, or, if desired, a portion thereof may be passed directly to some 75

intermediate point of the coking chamber 4, such as the upper part thereof and another portion of the coking stock merged with the highly heated condensate before this condensate is passed to the coking chamber 4 in any one of the ways already described.

The coking stock is thus intimately contacted with the highly cracked products and the vaporizable constituents thereof separated and these together with cracked vapors are passed to the dephlegmator 5 as before described. The liquid constituents of the coking stock are retained in the lower portion of the coking chamber 4 and are therein maintained at a coking temperature by the highly heated cracked products from coil 3 and reduced to coke. The coke produced in accordance with my invention is substantially free from cracked tar and other heavy tar-like products initially carried over from the coking zone, and has been found to contain more lump and to be of a better granular structure than coke produced in accordance with prior processes. As the coke gradually builds up in the coking chamber 4, the point of introduction of the cracked stream is correspondingly raised in a well known manner, and when the coking chamber 4 has the desired quantity of coke therein the charge to this particular coking chamber may be cut off and diverted to another similar coking chamber. The thus formed coke may be withdrawn from the coking chamber 4 through the manway 48.

To assist fractionation in the fractionator 9, the distillate, comprising naphtha, or other light distillate, collected in the receiver 39 may be withdrawn through the line 42 and forced by means of a pump 48 through a line 49 to the upper portion of the fractionator 9. This distillate which acts as a refluxing medium directly contacts the upwardly rising vapors and at least a portion thereof is vaporized, the unvaporized portion collecting with the reflux condensate in the lower portion of the fractionator 9 to constitute the charge for the coils 2 and 3.

The dephlegmator 5 and the flash tower 29 have been shown as being divided by means of suitable trap-out trays. It is to be understood that in lieu of using one vessel divided in the manner shown, two vessels may be used for each to accomplish the same results.

In carrying out a combined cracking and coking operation in accordance with my invention wherein a motor fuel of the gasoline boiling range is collected in the distillate receiver 12 and lump coke of an exceptionally good granular structure produced in the coking chamber 4, as well as a heavy gravity fuel oil collected in the lower portion 7 of the dephlegmator 5 and either withdrawn through the line 25 by opening the valve 26 or through the line 32', the clean cycle condensate collected in the lower portion of the fractionator 9 at a temperature of from about 575°-675° F. is forced while being maintained under a superatmospheric pressure of from 200 to 500 pounds per square inch through the coils 2 and 3 wherein it is raised to an outlet temperature of from about 975° to 1075° F. A coking stock comprising unvaporized constituents of the charge oil and condensate resulting from the dephlegmation of cracked vapors but substantially free from cracked heavy tar-like products is withdrawn from the trap-out tray 8 at a temperature of about 725° to 775° F. and forced to the transfer line 17 where it merges with the cracked stream. The pressure on the cracked stream

either before or after the merging thereof with the coking stock may be reduced to about 125 to 400 pounds per square inch and the thus combined streams at the reduced pressure passed into the coking chamber 4 maintained at a temperature of about 830° to 900° F. Residual constituents of the oil introduced into the coking chamber 4 are retained therein and reduced to coke, the vaporous constituents passing to the lower portion of the dephlegmator 5 which may be maintained at a pressure of from 75 to 250 pounds per square inch by manipulation of the valve 21 and are therein dephlegmated to produce a cracked residuum, such as a cracked tar in the lower portion 7 and the coking stock which is separately collected on the trap-out tray 8. The vapors passing through the line 22 at a temperature of about 650° to 750° F. are fractionated in the fractionator 9 to obtain an overhead fraction having an end point within the range of about 325° to 425° F.

The cracked tar or heavy tar-like product which is at a superatmospheric pressure is introduced into the lower portion 32 of the flash chamber 29, maintained at a pressure of from about atmospheric to about 25 pounds per square inch, and therein flashed to separate a heavy gravity fuel oil of from about 0 to 10° A. P. I. depending upon the charging stock which is withdrawn through the line 32'. The vaporous constituents rising upwardly through the trap-out plate 33 are contacted by fresh charge, in the nature of a heavy oil, such as a reduced crude, introduced through the line 34 and preferably preheated to a temperature about 200° to 500° F. and are therein dephlegmated. The unvaporized portion of the fresh charge together with condensate resulting from dephlegmation of the flashed vapors are forced at a temperature of from about 500° to 650° F. through the lines 43 and 45 into the upper portion of the dephlegmator 5 to constitute the charge oil therefor. This charge oil or fresh charge oil from an extraneous source is treated in the manner aforesaid to produce the products obtained in accordance with my invention.

The temperature-pressure conditions maintained on the oil passing through the cracking coils 2 and 3 are such as to accomplish vapor phase cracking, it being understood, of course, that higher or lower pressures and temperatures throughout the entire system may be maintained depending on the particular stock being treated. The relative amounts of cracked products from the heating coil 3 and coking stock from trap-out tray 8 in dephlegmator 5, admixed with the cracked products in line 17, should be proportioned with respect to each other so that the temperature within the coking drum 4 will be adequate to form a solid coke residue.

While I have shown and described the preferred embodiment of my invention, I wish it to be understood that I do not confine myself to the precise details of construction herein set forth, by way of illustration, as it is apparent that many changes and variations may be made therein, by those skilled in the art, without departing from the spirit of the invention, or exceeding the scope of the appended claims.

I claim:

1. In a method of treating petroleum oil to produce motor fuel and coke wherein a clean condensate stock is subjected to high-temperature cracking treatment in a tubular heating coil, the products thereafter transferred into an

- enlarged coking chamber at a temperature adequate to coke additional heavier hydrocarbon oil introduced therein and overhead vaporous products resulting from the cracking and coking treatment fractionated to separate a desired distillate therefrom, the improvement which comprises initially fractionating the overhead vaporous products in a primary fractionating zone to separate a high-boiling fraction therefrom, separately withdrawing the high-boiling fraction, subjecting said withdrawn fraction to further distillation to liberate lower-boiling constituents therefrom, withdrawing unvaporized residue resulting from said further distillation as a fuel oil product, passing vapors liberated during said further distillation in direct heat exchange with fresh charging oil containing vaporizable and unvaporizable constituents to preheat said fresh charging oil and condense higher-boiling constituents of said liberated vapors, subjecting vapors remaining uncondensed in said primary fractionating zone to further fractionation in a secondary fractionating zone, introducing the preheated fresh charging oil into said secondary fractionating zone and passing the same in said zone in direct countercurrent contact with cracked vapors therein to condense higher-boiling constituents of said cracked vapors and to vaporize lower-boiling constituents of said fresh charging oil, separately withdrawing a mixture of unvaporized constituents of said charging oil and cracked condensate from said secondary fractionating zone, introducing said mixture into the enlarged coking chamber as coking stock therefor, subjecting vapors remaining uncondensed in said secondary fractionating zone to further fractionation in a tertiary fractionating zone to condense constituents boiling above the end point of the desired distillate, separately withdrawing the resulting condensate and passing it to said tubular heating coil as charging stock therefor and subjecting vapors remaining uncondensed in said tertiary fractionating zone to further condensation to separate the desired distillate therefrom.
3. In the method of treating petroleum oil to produce motor fuel and coke wherein a clean condensate stock is subjected to high-temperature cracking treatment in a tubular heating coil, the products thereafter transferred into an enlarged coking chamber at a temperature adequate to coke additional heavier hydrocarbon oil introduced therein and overhead vaporous products resulting from the cracking and coking treatment fractionated to separate a desired distillate therefrom, the improvement which comprises initially fractionating the overhead vaporous products in a primary fractionating zone to separate a high-boiling fraction therefrom, separately withdrawing the high-boiling fraction, subjecting said withdrawn fraction to further distillation to liberate lower-boiling constituents therefrom, withdrawing unvaporized residue resulting from said further distillation as a fuel oil product, passing vapors liberated during said further distillation in direct heat exchange with fresh charging oil containing vaporizable and unvaporizable constituents to preheat said fresh charging oil and condense higher-boiling constituents of said liberated vapors, withdrawing a mixture of unvaporized constituents of said charging oil and condensate resulting from contacting said vapors liberated during said further distillation with fresh charging oil and conducting said mixture into the enlarged coking chamber to be therein reduced to coke, subjecting vapors remaining uncondensed in said primary fractionating zone to further fractionation to separate a desired distillate product therefrom.

VICTOR STAPLETON.
